UNITED STATES PATENT OFFICE

JOHN LE MAY, OF AURORA, ILLINOIS, ASSIGNOR TO AURORA METAL CO., OF AURORA, ILLINOIS, A CORPORATION OF ILLINOIS

SEPARABLE DIE

Application filed April 7, 1930. Serial No. 442,351.

This invention relates to improvements in dies or molds, and more especially a separable die.

For the purpose of illustrating my invention, I have shown such a die adapted for casting by the use of a vacuum or reduced pressure; although it is obvious that the invention may be used in connection with other casting processes.

One of the features of my invention is the provision of means for venting air confined between contacting surfaces of parts of such a die.

Another feature of my invention is the provision of such a die adapted for casting a plurality of bodies simultaneously, the gates to the several mold cavities arranged in diverging relationship, lessening or preventing movement or distortion of the die or parts thereof due to shrinkage caused by cooling or freezing of the metal in the gates.

Another feature of my invention is the provision of diverging gates in a separable die arranged so that as the gates shrink, the parts of the die are separated, thus partially releasing the castings from the die and serving to relieve the pressure of the castings upon the walls of the mold cavities which otherwise would be caused by shrinkage of the gates.

Other features and advantages of my invention will appear more fully as I proceed with my specification.

In that form of device embodying the features of my invention shown in the accompanying drawings, Fig. 1 is a view in perspective of the die, Fig. 2 is a view taken as indicated by the line 2 of Fig. 1, showing also the nozzle of the die receiver; Fig. 3 is a view taken as indicated by the line 3 of Fig. 2, Fig. 3^a is a view similar to Fig. 3, showing the parts of the die somewhat separated, Fig. 4 is a vertical sectional view of a body cast in the die, Fig. 5 is a vertical sectional view of the die receiver and nozzle showing the die inside, Fig. 6 is a top plan view of the die showing the clamp, and Figs. 7 and 8 are vertical sectional views of a modified form.

As shown in the drawings, the die as here shown includes two parts 10, and 11, adapted

to be held together by the encircling strap 12 and set screw 13. When the two parts are placed together there is formed in the die the mold cavity 14 in which is cast a hollow cylindrical or roller shaped body 14^a as shown in Fig. 4.

It will be seen that the body 14^a is hollow in the center as indicated by 14^b and that this hollow space is produced by providing the two parts of the die 10 and 11 with the core projections 15 and 16, the ends of the same having similarly shaped contacting surfaces (here shown as circular) 17. It is to be noted that the die is adapted for the simultaneous casting of two bodies 14^a and that the parts just described are duplicated.

In a die of this kind, whenever there are two parts with similarly shaped contacting surfaces adjacent the mold cavity air is likely to be trapped between said surfaces. When the molten metal enters the mold cavity the heat will cause this air to expand the blow into the mold cavity causing defects in the casting, unless some means are provided to prevent this. One of the features of my invention is the provision of means to vent any air thus trapped between such contacting surfaces. I accomplish this by providing an air vent 18 through one of the parts 10 of the mold for each casting, such vent having its inner end as indicated by 18^a at the junction of said contacting surfaces and the other end as indicated by 18^b at the outer surface of the die. Any air trapped between the contacting surfaces 17, 17, can escape through the vent 18 and will not blow into the mold cavity 14.

In Fig. 5 the die is shown for casting with reduced pressure. In this figure, 19 indicates a receiver from which air can be exhausted through the pipe outlet 20. The receiver carries a metal inlet nozzle 21 at the bottom adapted for insertion into molten metal. The bottom of the die has a metal inlet 22 adapted to register with the opening 23 in the nozzle 21 when the die is in place in the receiver as shown in Fig. 5 and held down by the spring pressed plunger 24.

In the casting operation, air is exhausted from the interior 19^a of the receiver 19. Although the parts of the die 10 and 11 are

placed together in contact with each other, the joints are not air tight. Consequently there are provided air escape passages between the parts of the die leading from the 5 mold cavities to the interior of the receiver. When air is exhausted from the receiver it will therefore be drawn out of the mold cavities and molten metal drawn or sucked up into such cavities by atmospheric pressure.

10 As stated above, the die is adapted for casting a plurality of bodies (here shown as two) at the same time. The metal inlet to the die is indicated by 22. From this inlet there is a gate 25 leading to each mold cavity. In 15 order to prevent or lessen distortion or movement of the mold or parts thereof due to shrinkage caused by cooling of the metal in the gates 25, 25, said gates are made to diverge from each other in their paths from the inlet 20 22 to the cavities 14, 14 (see Fig. 2). It is to be noted that the upper side of the gate as indicated by 26 is wedge-shaped, so that as the gates 25 shrink, the upper ends being held by the castings in cavities 14, the wedge-shaped portion at 26 is raised (see Fig. 3a) thus separating the two halves of the die. This serves to relieve the pressure of the castings upon the walls of the cavities 14 due to the shrinkage of the gate 25 and further partially 25 releases the castings from the die. It is of course necessary to use a form of clamp which will yield somewhat to permit this separation of the parts of the die. This may be accomplished by providing the clamp 12 30 with an inwardly bent spring portion as shown in Fig. 6.

35 In Figs. 7 and 8 I have shown another form of die with diverging gates. In this form, the mold cavities 27, 27 are in the upper part 40 28 of the die. 29, 29 indicate the cores. The lower part of the die is indicated by 30. 31, 31 indicate air vents. In this form of die the diverging gates 32, 32 are cut into the conical surface 28a on the inner side of the die 45 part 28. If desired, however, these gates may be cut in the lower part 30. The cylindrical bodies cast in the cavities 27, 27 are indicated by 33. When the castings cool, the parts 28 and 30 of the die are separated as shown in Fig. 8. This is caused by shrinkage of the 50 gates 32, 32. This separation of the parts of the die relieves the pressure between the castings and partially releases the castings 55 from the die.

While I have shown and described certain embodiments of my invention, it is to be understood that it is capable of many modifications. Changes, therefore, in the construction and arrangement may be made without departing from the spirit and scope of the invention as disclosed in the appended claim, in which it is my intention to claim all novelty inherent in my invention as broadly as possible, in view of the prior art.

What I regard as new, and desire to secure by Letters Patent, is:

A die including separable parts having a plurality of mold cavities for simultaneously casting a plurality of bodies, said die having a metal inlet and a gate leading therefrom to each mold cavity, said gates diverging at an angle from the metal inlet to the cavities and lying between parts of the die, one of the die parts having a slanting surface lying in the angle formed by the said diverging gates, whereby shrinkage of the gates will cause movement of said gates and pressure on said slanting surface to cause a separation of the die parts.

In testimony whereof, I hereunto set my hand this 4th day of April, 1930.

JOHN LE MAY.
